(57) CLAIM

The ornamental design for a body fat scale, as shown and described.

DESCRIPTION

FIG. 1 is a first perspective view of a body fat scale showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the body fat scale thereof;

FIG. 10 is a perspective view of another state of the body fat scale thereof; and,

FIG. 11 is an enlarged view of the selected portion 11 in FIG. 1.

The broken lines shown in the drawings depict portions of the body fat scale that form no part of the claimed design.
